EARRING TREE

Chester A. Chamberlain, Flushing, N. Y.

Application February 1, 1950, Serial No. 7,630

Term of patent 3½ years

(Cl. D80—9)

To all whom it may concern:

Be it known that I, Chester A. Chamberlain, a citizen of the United States, residing at Flushing, in the borough of Queens and State of New York, have invented a new, original, and ornamental Design for an Earring Tree, of which the following is a specification, reference being had to the accompanying drawing, forming part thereof, and in which—

Fig. 1 is a front elevational view of the earring tree in which my design is incorporated;

Fig. 2 is a side elevational view thereof; and

Fig. 3 is a top plan view thereof.

I claim:

The ornamental design for an earring tree, as shown.

CHESTER A. CHAMBERLAIN.
